UNITED STATES PATENT OFFICE

132,871

DESIGN FOR A BLACK-OUT UNIT FOR A COMBINATION TAILLIGHT, AND SERVICE AND STOPLIGHT LENS

Walter C. Thee, United States Army

Application January 22, 1942, Serial No. 105,367

Term of patent 3½ years

To all whom it may concern:

Be it known that I, Lieutenant Colonel Walter C. Thee, United States Army, a citizen of the United States, have invented a new, original, and ornamental Design for a Black-out Unit for a Combination Taillight, and Service and Stop Light Lens, of which the following is a specification, reference being had to the accompanying drawing, forming part thereof.

Fig. 1 is a front elevational view of the black-

out unit for a combination taillight, and service and stop light lamp, showing my new design.

Fig. 2 is a side elevational view thereof, and Fig. 3 is a rear elevational view thereof.

I claim:

The ornamental design for a black-out unit for a combination taillight, and service and stop light lens, as shown.

WALTER C. THEE.
